UNITED STATES PATENT OFFICE.

BENJAMIN WOLHAUPTER, OF CHICAGO, ILLINOIS.

TIE-PLATE.

SPECIFICATION forming part of Letters Patent No. 700,998, dated May 27, 1902.

Application filed September 30, 1901. Serial No. 77,057. (No model.)

To all whom it may concern:

Be it known that I, BENJAMIN WOLHAUPTER, of Chicago, in the county of Cook and State of Illinois, have invented certain new and useful Improvements in Tie-Plates; and I do hereby declare that the following is a full, clear, and exact description thereof, reference being had to the accompanying drawings, and to the letters of reference marked thereon, which form a part of this specification.

This invention relates to improvements in railway-tie plates which are adapted to be interposed between the rails and ties for the purpose of preventing the wearing away of the ties. One of the primary requisites of tie-plates of this character in order to insure the general adoption thereof under practical conditions is that the plates shall possess ample strength to withstand the excessive strains and shocks brought thereon by the weight of passing trains and be constructed to insure a permanent attachment to the ties and yet shall be made of such simple construction and contain such minimum amount of metal as to add comparatively little cost to a railway-track in connection with which they are used.

One of the principal objects of my invention is to provide an improvement in tie-plates of the character described which will enable tie-plates possessing the characteristics essential to a practical article to be economically manufactured with the use of a minimum amount of metal.

The invention has for its further object general improvements in the construction of tie-plates, as will hereinafter more fully appear.

The invention consists in the matters hereinafter set forth, and more particularly pointed out in the appended claims.

In the drawings, Figure 1 is a perspective view of a tie-plate made in accordance with my invention, showing also in perspective one end of a rail resting thereon. Fig. 2 is a transverse section of a tie, showing the plate illustrated in Fig. 1 attached thereto. Fig. 3 is a transverse section of a slightly-modified form of tie-plate and means for attaching the same to the tie. Fig. 4 illustrates the position of the fastening-prongs illustrated in Fig.

3 after the same have been driven into the tie. Fig. 5 is a view showing in side elevation an improved form of holding-prongs for 55 the plate. Figs. 6, 7, and 8 illustrate modified forms of the bearing-surface of the plate. Fig. 9 is a transverse section on line 9 9 of Fig. 8.

First referring to the construction shown 60 in Figs. 1 and 2, A designates the tie-plate as a whole, B the tie to which the plate is attached, and C the rail resting on the plate and secured to the tie by means of the usual spikes D. The body of said plate is generally 65 flat and is provided on its under surface with a plurality of parallel tapered flanges A' A' A² A², parallel with the side margins of the plate, and the flanges A² are located between the outer flanges. Said plate is provided with 70 a plurality of spike-holes a, three being herein shown, through which pass the spikes D, by which the rails are secured to the tie. The flanges A' A² are adapted to be driven their full length into the ties, whereby the 75 body of the plate rests firmly upon the upper surface of the tie. Said flanges are driven into the tie parallel with the grain thereof, so as not to cut the fiber of the tie and thereby weaken the same. The flanges A' A² give 80 stiffness to the plate and prevent the same from buckling under the heavy strain brought thereon and also aid to hold the plate in place on the ties.

In addition to the parallel flanges A' A², I 85 provide holding-prongs A³, which are cut out from the body of the plate and bent downwardly at right angles thereto. Said prongs are made considerably wider or deeper than the flanges A' A² and are located between the 90 exterior flanges, the same being shown in the drawings as located between the intermediate flanges A². Said prongs are generally triangular, each being divided from the body of the plate by two divergent cuts and being 95 bent or folded along the line of its base, one of said prongs being located adjacent to one of said flanges A² and the other prong adjacent to the other flange and out of line with the first-mentioned prong. The lower ends 100 of said prongs are preferably made as wide as practicable and are shown as provided with notches a³. Said prongs being made of the same thickness from the top to the bottom

thereto, adhere closely to the fiber of the tie when driven thereinto and afford effectual resistance to the accidental displacement of the plate due to jars incident to passing trains 5 or from other cause.

On the upper surface of the plates are formed a plurality of independent integral protuberances or elevations $a' a^2$. The protuberances a' are located over or nearly over 10 the intermediate flanges A^2 and may be placed either regularly or irregularly, while the protuberances a^2 are spaced at irregular intervals about the surface of the plate, principally between the planes of the intermediate flanges and the side margins of the plate. The upper surfaces of said protuberances are flat and are located in a common plane and constitute the bearing-surface on which the rail rests. Said bearing-surface for the rail 15 is made in the manner described for the purpose of allowing cinders, sand, and the like, which lodge between the rail and plate, opportunity to escape and prevent wear of the rail and plate by the grinding of such interposed foreign particles between the same. The protuberances $a' a^2$ are each separated 20 from adjacent protuberances by spaces of sufficient extent to permit free escape of such particles from the space between the rail and 25 the top surface of the plate.

As shown in Fig. 2, the protuberances a^2 are hollow on their under surfaces, so that the upper or bearing walls of said protuberances are not thicker than the body of the plate. 30 This construction results in a considerable saving of metal and at the same time does not weaken the plate, it being observed that the weight is brought upon the nearly-vertical parts, which constitute the circular walls of 40 said hollow protuberances.

The preferred manner of making tie-plates as described is as follows: Said plates are cut from bars previously rolled to give the same the desired cross-sectional form, said rolling 45 operation forming on the bars the flanges A' A^2 and a part or all of the protuberances $a' a^2$. The plates are thereafter punched to form the spike-holes a and are cut to provide the holding-prongs A^3 , said prongs being 50 thereafter bent downwardly into the position shown. In the rolling process the margins of the bar are turned downwardly to form the flanges A' , and the flanges A^2 are formed in suitable grooves in one of the forming-rolls. 55 The other forming-roll is provided with suitable recesses, in which are formed during the rolling operation the protuberances a' , located over the intermediate flanges A^2 , said recesses being spaced about the perimeter of 60 the roll to form the protuberances a' with regard to the end margins of the plates thereafter cut from the bar. The hollow protuberances a^2 are thereafter formed in the plate by punching or striking the metal there- 65 of upwardly by the use of suitable punching or swaging dies. If the protuberances $a' a^2$ be made solid, they may all be formed in the

rolling operation; but when a portion of the protuberances are made hollow practical difficulties are met which prevent the same from 70 being economically formed in the rolling process, the chief of which is the difficulty of gearing together forming-rolls to secure the registry or coöperation of elevations and depressions thereon by which may be formed 75 the hollow protuberances. The operation of forming the hollow protuberances a^2 is preferably effected by suitable dies having a plurality of rigid independent punches, so that all of said protuberances may be formed by 80 one operation. In this way of forming said protuberances I am enabled to form the same by the use of less metal than if they were rolled on the plate at the time the bar from which the plate is cut is subject to the rolling 85 operation.

The plate shown in Figs. 3 and 4 is provided with integral holding-prongs A^4 , which are bent downwardly from the plate and oppositely inclined at their lower ends, the prongs 90 shown as slightly converged. With this construction when the prongs are driven into the tie by reason of their obliquity with respect to the body of the plate the lower ends thereof are directed toward each other, and when 95 said prongs have been driven to their full length into the tie the lower end of each prong is bent inwardly and may cross the plane of the other, as shown in Fig. 4. This construction obviously affords a greater resistance to 100 the withdrawal of the prongs than where the said prongs are driven directly into the tie at right angles to the body of the plate. The lower ends of the prongs in either of the constructions shown may be provided with barbs 105 a^4 , as shown in Fig. 5, which when the prong is driven into the tie affords an additional resistance to the withdrawal of the prong and the displacement of the plate of which the prong forms a part. 110

In Figs. 6, 7, 8, and 9 I have illustrated modified forms of the protuberances for the plate A, the upper surface of which protuberances constitute the bearing-surface for the rail. In each of the constructions shown in 115 these figures the protuberances are formed entirely upon the upper surface of the plate and are formed in the rolling operation.

In Fig. 6 the protuberances a^6 are substantially square, while in Fig. 7 the protuberances a^7 are of general lozenge shape. In 120 each of these figures the protuberances are shown as arranged in rows which extend obliquely to the side and end margins of the plate; but similar protuberances may be irregularly arranged, as is the case in the construction shown in Fig. 1. In Figs. 8 and 9 the protuberances a^8 have the form of circular flanges or ribs which are raised above the surface of the plate and are disposed at irregular intervals upon said plate. In this case the upper margins of said ribs constitute the bearing-surface for said rail. The plate 125 shown in Figs. 6, 7, 8, and 9 may be provided

with holding-prongs, such as hereinbefore described.

Among the advantages of forming the bearing-surfaces for the rail on the upper surfaces of protuberances in the manner described is that a plate of ample strength may be made thereby with a much less quantity of metal than where the bearing-surface for the rail is formed on the principal surface of the plate or upon longitudinal ribs or elevations formed thereon. Moreover, said protuberances being separated from each other by spaces permit cinders and the like which lodge between the rails and the plate to escape therefrom in all directions and not be restricted in such escape to longitudinal channels or grooves between elevations or ribs when the bearing-surface of the plate is formed on such ribs.

It will be observed that in all of the forms shown the protuberances are so disposed as not to form rows parallel with the side margins of the body of the plate, thereby avoiding symmetrically-arranged obstructions to the free passage of the cinders and sand from the space between rail and plate.

The plate described is obviously inexpensive to manufacture and affords a structure of great strength as compared with the amount of metal contained therein.

I claim as my invention—

1. A tie-plate provided on its upper surface with a plurality of separated protuberances, the upper surfaces of which constitute the rail-bearing surface.

2. A tie-plate provided on its upper surface with a plurality of separated protuberances, the upper surfaces of which constitute the rail-bearing surface, and on its under surface with tie-engaging flanges.

3. A tie-plate provided on its upper surface with a plurality of separated protuberances, the upper surfaces of which constitute the rail-bearing surface, and holding prongs or flanges cut from the body of the plate and bent downwardly therefrom.

4. A tie-plate provided on its upper surface with a plurality of separated protuberances, the upper surfaces of which constitute the rail-bearing surface, and on its under surface with tie-engaging flanges arranged parallel with the side margins thereof, and holding prongs cut from the body of the plate between said flanges and bent downwardly from said plate.

5. A tie-plate provided on its upper surface with a plurality of separated protuberances, the upper surfaces of which constitute the rail-bearing surface, and on its under surface at or near the margins thereof with two tie-engaging flanges and with an intermediate flange or flanges depending from said plate between and parallel with said outer flanges, and holding-prongs cut from the body of said plate and bent downwardly from the plate.

6. A tie-plate provided on its upper surface

with elevated parts, the upper surfaces of which constitute the bearing-surface for the rail and on its lower part with rail-engaging flanges arranged parallel with the side margins of the plate, and holding-prongs cut from the body of the said plate between said flanges and bent downwardly therefrom.

7. A tie-plate provided on its lower surface with a plurality of parallel tie-engaging flanges and on its upper surface with separated protuberances, which form supporting-surfaces for the rail and which are located over one or more of the flanges.

8. A tie-plate provided on its upper surface with a plurality of hollow separated protuberances, the upper surfaces of which constitute the rail-bearing surface.

9. A tie-plate provided on its lower surfaces with tie-engaging flanges and on its upper surfaces in its parts between said flanges with a plurality of separated protuberances, formed by striking upwardly the metal of the plate, and which form rail-supporting surfaces.

10. A tie-plate provided on its upper surface with a plurality of separated protuberances, the upper surfaces of which constitute the rail-bearing surface, and on its lower surface with rail-engaging flanges, certain of said protuberances being located on the plate over one or more of the flanges, and others of said protuberances being located in the parts of the plate between the flanges and being struck up from the metal of the plate.

11. A rolled-metal tie-plate provided with tie-engaging flanges which extend throughout the length of the plate parallel with the side margins thereof, and separated protuberances on the upper surface of the plate, the upper surfaces of which constitute the rail-bearing surface, certain of said protuberances being located over the flanges and holding-prongs cut from the body of the plate between said flanges and turned downwardly therefrom.

12. A rolled-metal tie-plate provided with tie-engaging flanges, which extend throughout the length of the plate parallel with the side margins thereof, and separated protuberances on the upper surface thereof, the upper surfaces of which constitute the rail-bearing surface, certain of said protuberances being located directly over the flanges and being spaced along said flanges, and others thereof being located between the flanges and made hollow with their upper walls no thicker than the body of the plate.

13. A rolled-metal tie-plate provided with tie-engaging flanges which extend throughout the length of the plate parallel with the side margins thereof and adjacent to said margins, intermediate flanges parallel with said outer flanges, separated protuberances on the upper surfaces of the plate, the upper surfaces of which constitute the rail-bearing surface, certain of said protuberances being located directly over the intermediate flanges and spaced at equal distances apart, and holding-

prongs cut from the body of the plate between said intermediate flanges and turned downwardly therefrom.

14. A rolled-metal tie-plate provided on its upper surface with separated protuberances, the upper surfaces of which constitute the rail-bearing surface, and prongs cut from the body of the plate and bent downwardly therefrom, said prongs being provided on their lower ends with barbs.

15. A tie-plate provided with means for attaching it to a tie, and provided on its upper surface with hollow separated protuberances, the upper walls of which constitute the bear-

ing-surface of the plate, said protuberances 15 being irregularly spaced upon the plate.

16. A tie-plate provided on its upper surface with a plurality of separated circular protuberances.

In testimony that I claim the foregoing as 20 my invention I affix my signature, in presence of two witnesses, this 27th day of September, A. D. 1901.

BENJAMIN WOLHAUPTER.
